Attn:

UNITED STATES PATENT OFFICE.

EMMETT LEROY QUIGLEY, OF SISTERSVILLE, WEST VIRGINIA.

GAS BURNER.

Application filed June 13, 1922. Serial No. 567,888.

To all whom it may concern:

Be it known that I, EMMETT L. QUIGLEY, a citizen of the United States, residing at Sistersville, in the county of Tyler and State 5 of West Virginia, have invented a new and useful Gas Burner, of which the following is a specification.

This invention relates to gas burners of the type known as low pressure burners.

10 The primary object of the invention is to construct a burner of this character so that comparatively little draft will be necessary to effect complete combustion, thereby cutting down the amount of smoke stack 15 usually required about one-half.

Another object of the invention is to provide a burner of this character for use in connection with the fire box of a boiler or furnace so constructed as to render it impossible to burn off the tops of the burner 20 tubes, thus greatly prolonging the life of the burner.

Another object is to construct a burner of this character which will generate steam 25 quickly and hold it better with the consumption of a minimum amount of gas.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made 35 within the scope of what is claimed without departing from the spirit of the invention.

In the accompanying drawings:—

Figure 1 represents a side elevation of a 40 burner constructed in accordance with this invention with parts broken out and in section.

Fig. 2 is a top plan view thereof, and

Fig. 3 is an end elevation.

45 In the embodiment illustrated, the burner constituting this invention comprises a cast iron main burner holding frame 1 preferably rectangular in form and the top and bottom bars of which are bolted to cast iron cross bars 2 and 3 which operate in connection with the top and bottom bars of the main frame to clamp the burner tubes 5 in place, the said cross bars and frame bars being recessed in their opposed faces to 50 form to the shape of the tubes for securely

clamping them in position, as is shown clearly in Fig. 2.

The end bars 4 of the main frame are extended below the bottom bar thereof to provide legs 4^a on which is mounted the gas 60 supply pipe 6, said pipe 6 being secured to the legs by stirrups 7 which extend transversely through said legs and are held in operative position by nuts 8.

The gas supply pipe 6 is equipped at one 65 end with a removable cap 9 while the opposed end thereof is screw threaded for connection with a conduit (not shown) through which the gas is conducted to the pipe.

The burner tubes 5 are of a length and 70 diameter which has been determined by many experiments to insure the formation of a proper mixture in these tubes.

Extending upwardly from the supply pipe 6 into the tubes 5, are a plurality of 75 gas jet tubes 10, one of which enters each of the tubes 5 and is provided at its terminal with a drilled opening 11 the size of which and the length of the tubes has been determined by experiments to insure the proper 80 positioning of these tubes 10 within the tubes 5 so that they will operate when the burner is lit to draw in air behind them from the open lower ends of the tubes 5, thereby insuring a proper mixture to produce 85 complete combustion.

When a burner of this character is installed in the fire box of a boiler (not shown) said fire box is rendered absolutely 90 air tight by any suitable means such as sheet iron and fire clay placed over the grate bars and around the top of the burners, excluding all air except that which enters through the burner tubes 5 which mixing with the 95 gas supplied through the tubes 10, provides a highly combustible and cheap mixture.

This arrangement and mounting of the burners requires very little draft in the fire box, and hence the amount of smoke stack 100 for producing such draft may be cut down to about one-half the amount ordinarily required for this purpose. This cutting down of the smoke stack used, results in a great saving of time and labor in erecting boilers, 105 particularly portable boilers, such as are used in drilling outfits and the like.

The use of the heavy cast iron cross bars at the top of the burner between which the burner ends are clamped and which extend 110

through the grate bars in the fire box renders it substantially impossible to burn off the tops of the tubes 5 which frequently occurs when plate iron is used for supporting these tubes or when the tubes extend up through the grate bars without any protection.

The provision of the removable cap 9 for the gas supply pipe 6 provides for the 10 cleaning out of this pipe by removing said cap and blowing out the pipe.

I claim:—

A burner of the class described comprising a rectangular supporting frame having 15 the end members thereof extended below the bottom member, a gas supply pipe mounted on the extensions of said end members, cross bars arranged to operate in connection with the top and bottom bars of 20 said frame to form burner tube clamps, said cross bars and frame bars being recessed in their opposed faces to conform to the shape of the tubes to be clamped between

them, whereby the tubes may be readily assembled and individual tubes removed when 25 desired, burner tubes carried by said frame and clamp between said cross bars with their lower ends spaced from the supply pipe, said tubes being open at both ends, 30 gas supply pipes leading from said main gas supply pipe and extended into said burner tubes, said gas supply pipes being of less diameter than the burner tubes and provided at their inner ends with nozzles 35 discharging into said burner tubes and operating to suck into the burner tubes air which is combined with the gas to form a highly combustible mixture.

In testimony that I claim the foregoing as my own, I have hereto affixed my signature in the presence of two witnesses.

EMMETT LEROY QUIGLEY.
